1 Claim. (Cl. 307—88.5)

This invention relates to monostable multivibrators and is directed to a reduction in the gain requirements of transistors employed in such circuits and an improvement in maximum limits of pulse durations which may be obtained.

In order for a monostable multivibrator to operate with an output which is stable and of predictable duration for a given bias setting, it is necessary that it operate in a saturated state. This requires high gain in the stages and, if transistors are used, requires expensive high gain types of transistors. If the gain of the transistors is too low, or the duration of the pulse too long, the multivibrator will become astable and free-running.

It is an object of this invention to provide a transistorized multivibrator circuit which may utilize low cost, low gain transistors and still operate in a stable and predictable manner.

It is a further object of the invention to provide a multivibrator circuit which will remain stable while producing output pulses of longer duration than could be stably produced by prior circuits.

These and other objects and advantages of the invention are realized by a circuit having a capacitive coupling between the output of the first stage and the input of the second, and a network shunting this coupling means, the network being composed of a series arrangement of a resistor and a diode, the resistor being shunted by a capacitor and the diode being poled to offer a low impedance to base current in the second stage.

The single figure of the drawing is a schematic diagram of a circuit embodying the invention.

In the drawing the multivibrator comprises a pair of transistors T_1 and T_2 indicated as being of the PNP junction type, with their emitters connected by way of a common resistor R_3 to a positive terminal 1 of a source of supply voltage indicated as $B+$. This terminal is connected to ground through a pair of serially connected resistors R_1 and R_2 , the junction of which is connected to the base of T_1 . The collectors of T_1 and T_2 are connected to ground through respective resistors R_5 and R_6 . The collector of T_1 is coupled to the base of T_2 by a capacitor C_1 . The base of T_2 is connected to ground through a variable resistor R_7 . There is provided a terminal 2, connected to the collector of T_1 , at which is applied to the multivibrator a series of positive-going triggering impulses indicated by the graph 3.

The portion of the circuit which has been described constitutes a monostable multivibrator in accordance with the prior art. In its operation the circuit is normally so biased by the voltage divider R_1 , R_2 that the transistor T_1 is cut off, with the voltage at the base of T_1 somewhat positive with respect to that at its emitter. T_2 is conduct-

2

ing to saturation with the voltage at its emitter substantially equal to that at its collector and the voltage at its base negative with respect thereto.

The application of a triggering impulse 3 at terminal 2, 5 causes the collector of T_1 to become more positive and the base of T_2 to do likewise. This reduces conduction in T_2 , making the emitters of both T_1 and T_2 become more positive and initiating conduction in T_1 . Conduction in transistor T_1 causes its collector to go more positive and the base of T_2 to follow. This regenerative action culminates in a complete reversal of the original conductive state, with T_2 entirely cut off and T_1 conducting to saturation. The voltage at the base of T_2 now begins to fall toward ground accompanied by current flow through R_7 and R_5 . 10 The setting of R_7 governs the rate of current flow and thus determines the pulse duration.

If the transistor T_2 is of relatively low gain the base bias current in R_7 may not allow enough collector-emitter current in T_2 to keep it in saturation with the result that the 15 emitter potential will rise toward $B+$, become more positive than that at the base of T_1 , and cause T_1 to start conducting. This will initiate a free-running condition of the multivibrator. This condition is most apt to occur when an output pulse of long duration is required and R_7 is increased in value to provide a long time constant $R_7 C_1$. This reduces the base current of T_2 to a value which will not keep T_2 saturated.

In accordance with the invention the collector of T_1 is connected by a resistor R_4 in series with a diode D_1 to the base of T_2 . The resistor is shunted by a capacitor C_2 . This causes an increase in T_2 base bias current due to direct current flow through R_4 and R_5 to ground. The 20 resistance of R_4 is chosen to be small enough so that the base current of T_2 will always be sufficient to keep it saturated, regardless of the magnitude of resistor R_7 .

During the timing interval of the multivibrator pulse the resistor R_4 is isolated from the $C_1 R_7$ timing function because the positive pulse appearing at the collector of T_1 , acting through the capacitor C_2 , causes the diode D_1 25 to be cut off. The C_2 , R_4 , D_1 network combination acts only during the quiescent state and thus does not load the timing network during the pulse.

What is claimed is:

1. In a monostable multivibrator comprising a pair of transistors each having an input circuit and an output circuit, regenerative feedback means coupling said transistors including, capacitive means coupling the output circuit of a first of said transistors to the input circuit of the second, resistive means providing a discharge path for said capacitive coupling means, means normally biasing 30 said first transistor to cut-off, and means applying voltage impulses to said capacitive coupling means and said output circuit of said first transistor of a magnitude and polarity to reverse the quiescent conductive states of said transistors; the improvement which comprises: a network shunting said capacitive coupling means, said network comprising a series arrangement of a resistor and a diode, 35 and a capacitor shunting said resistor.
